Inventor

UNITED STATES PATENT OFFICE.

ANDREW J. QUIST, OF MOUNT JEWETT, PENNSYLVANIA.

RUBBER-HEEL REINFORCEMENT.

Application filed August 19, 1921. Serial No. 493,632.

To all whom it may concern:

Be it known that I, ANDREW J. QUIST, a citizen of the United States, residing at Mount Jewett, in the county of McKean and 5 State of Pennsylvania, have invented a new and useful Rubber-Heel Reinforcement, of which the following is a specification.

The device forming the subject matter 10 of this application is a rubber heel, and one object of the invention is to give stiffness to a curved heel, so that it will form a tight joint about its periphery, when nailed down, thereby eliminating the use of cement.

Another object of the invention is to provide 15 novel means for reinforcing the heel.

A further object of the invention is to provide novel means for preventing the securing 20 nails from being pulled through the heel.

It is within the province of the disclosure 25 to improve generally and to enhance the utility of devices of that type to which the invention appertains.

With the above and other objects in view, 30 which will appear as the description proceeds, the invention resides in the combination and arrangement of parts and in the details of construction hereinafter described and claimed, it being understood that, within the scope of what is claimed, changes in 35 the precise embodiment of the invention shown can be made without departing from the spirit of the invention.

In the accompanying drawings:—

Figure 1 shows in plan, a heel constructed 40 in accordance with the invention; Figure 2 is a side elevation; Figure 3 is a rear end elevation; Figure 4 is a section on the line 4—4 of Figure 1; and Figure 5 is a section on the line 5—5 of Figure 1.

The numeral 1 marks a heel, made of rubber, the outer surface of the heel being convexed longitudinally of the heel, as indicated at 2, and being convexed transversely of the

heel as indicated at 3. The inner surface 45 of the heel is concaved longitudinally of the heel as shown at 4 and is concaved transversely of the heel as shown at 5.

An insert or reenforcement 6, preferably made of canvas, is embedded in the heel 1. 50 Washers 7 may be superposed on the insert or reenforcement 6, the heel having openings 8 aligned with the openings of the washers and adapted to receive securing elements.

The reenforcement serves to stiffen the 55 heel so that, when the heel is nailed down, the heel will make a tight joint, about the entire periphery, without the use of cement. The washers 7 serve to prevent the nails from being pulled through the heel, the 60 nails, of course, being inserted into the openings 8, and the heads of the nails engaging the washers 7.

What is claimed is:—

A rubber heel having an outer surface 65 which is convexed longitudinally of the heel and transversely of the heel, the inner surface of the heel being concaved longitudinally of the heel and transversely of the heel; a flexible textile insert completely housed 70 within the heel and conforming to the convexity and the concavity of the heel, the insert conforming in peripheral outline to the peripheral outline of the heel, the insert being located approximately midway between the 75 outer surface of the heel and the inner surface of the heel; and washers mounted on the insert, the washers being completely housed within the heel, and the heel having openings leading to the washers. 80

In testimony that I claim the foregoing as my own, I have hereto affixed my signature in the presence of two witnesses.

ANDREW J. QUIST.
